SUCTION CLEANER

Donald G. Smellie, Canton, Ohio, assignor to The Hoover Company, North Canton, Ohio, a corporation of Ohio

Application October 30, 1933, Serial No. 695,781

6 Claims. (Cl. 240—2)

The present invention relates to suction cleaners in general and particularly to new and novel improvements in lighting means in suction cleaners. More specifically the invention comprises the provision of lighting means which are positioned in the main casing of the suction cleaner, and which direct light rays forward of the cleaner nozzle.

It is an object of the present invention to provide a new and improved suction cleaner. It is another object to provide new and improved lighting means in a suction cleaner. Still another object is the provision, in a suction cleaner, of lighting means which are positioned within the main casing of the cleaner in a manner which makes replacement easy and injury unlikely. A still further object is the provision, in a suction cleaner, of lighting means which are positioned within the body of the cleaner and which include means to reflect light rays upwardly to higher point in the cleaner and then downwardly onto the surface covering undergoing cleaning. These and other more specific objects will appear from a reading of the following specification and claims and upon consideration of the attached drawing to which they relate.

In the drawing in which a preferred embodiment of the invention is disclosed:

Figure 1 is a side elevation of a suction cleaner embodying the present invention, a section through the cleaner nozzle and main casing being taken upon the line 1—1 of Figure 2;

Figure 2 is a front elevation of the cleaner shown in Figure 1;

Figure 3 is a view in perspective of the lighting unit removed from its seat in the cleaner casing;

Figure 4 is a view upon the line 4—4 of Figure 1, the lamp bulb being removed.

Figure 5 is a section upon the line 5—5 of Figure 4.

Lighting means in a suction cleaner should be so positioned that they direct light rays upon the surface covering undergoing cleaning immediately forward of the cleaner nozzle. They should be so positioned that they are easily removable in order that they may be replaced upon light failure, or injury. They should also be so positioned that they are not readily injured by contact with foreign objects such as articles of furniture positioned upon the surface covering undergoing cleaning. In the suction cleaner constructed in accordance with the present invention light means have been incorporated into the cleaner construction which embody all of the

desirable features stated. The construction is as hereinafter fully described.

Referring again to the drawing a suction cleaner is disclosed in which the main casing is seen to comprise a nozzle 1, including front and rear walls 2 and 3, a fan chamber 4, a motor casing 5, and an exhaust outlet 6. The nozzle 1 is interiorly connected by an air passageway 7 to the fan chamber 4, there being a rotatable fan 8 positioned within that chamber which functions to create a reduced pressure to draw air into the nozzle 1, through the air passageway and chamber and exhaust it through the outlet 6 into a removably attached dust bag 9. The driving motor for the fan 8 is not shown but is of any suitable type being positioned within the casing 5. The cleaner is provided with front wheels 10, 11 and rear wheels 12, 12 and there is provided a pivoted handle 13 through which the user may exert a propelling force.

The front and top wall 2 of the nozzle 1 merges into the contour of the motor casing 5 in a smooth curve across substantially the entire width of the motor with the exception of the central portion thereof, in which a raised and rounded wall 14 is formed to provide a forwardly facing opening the edges of which are enclosed and protected by a rubber guard member 15. The opening formed by the wall 14 and defined by the guard member 15 opens into a space formed within the casing between the forward portion of the curved wall of the motor casing 5 and the rear wall 3 of the nozzle 1, as clearly shown in Figure 1.

Immediately below the wall 14 is removably positioned the light-creating unit 16. This unit comprises the sheet metal member formed as an elongated double back wall 17 and a curved portion 18 formed integrally therewith which faces upwardly toward the wall 14. Portion 18 is adapted to function as a reflector. The member 16 carries a socket 19, at the end of reflector 18 which includes suitable contacts 20, 20 to which are connected current-carrying leads 21, 21. As is clearly shown in Figure 1 a lamp 22 is adapted to be seated in the socket member 19 and when so positioned overlies the reflector 18.

The unit 16 is manually removable from within the casing without using tools. The folded upper edge of wall 17 extends within a downwardly facing channel 23 in the underside of top wall 2 of the nozzle. A spring 24 of the leaf type is carried by top of the wall 17 and contacts the bottom of the channel 23 forcing the member downwardly and the bottom edge of the wall into the seat or groove 25 which faces the channel 23. Reflector 55

- unit 16 is inserted in its seat through urging the top of wall 17 into the channel 23 compressing the spring 24 to enable the bottom of the wall to clear the top of channel 25. When the wall 17 is immediately above the channel 25 and parallel with the wall 3, spring 24 is permitted to urge the unit downwardly and the bottom edge of the wall seats within groove 25. The removal of the unit is exactly the reverse operation.
- 10 With the lighting unit positioned within the recess in the main casing light rays are thrown upwardly into the housing formed by the wall 14 and in order to deflect these rays downwardly ahead of the nozzle 1 a second reflector, indicated 15 at 26, is provided which extends between the front of the motor casing 5 and the wall 14 at the required angle.
- I claim:
1. In a suction cleaner, a main casing including 20 a nozzle and fan chamber, a lighting unit positioned in said casing and shielded from direct view, said casing being formed with a forwardly facing opening which is positioned above said unit, and reflecting surfaces to direct light rays 25 upwardly from said unit and then forwardly through said opening and onto a surface covering forward of said nozzle.
2. In a suction cleaner including a casing and 30 means movably supporting it, said casing being formed with a forwardly facing opening, said casing being formed with an interior recess connected to said opening and itself having an entrance on the underside of said casing, and a light unit positioned in said recess, said unit being removable from said recess thru the entrance on the underside of said casing.
3. In a suction cleaner including a casing and 35 means movably supporting it, said casing being formed with a forwardly facing opening, said

casing being formed with an interior recess connected to said opening and itself having an entrance on the underside of said casing, a seat in said recess, and a light unit in said seat, said unit being manually removable without tools from said seat and from said recess thru said entrance on the underside of said casing. 5

4. A suction cleaner including a casing and means movably supporting it, said casing being formed with an interior recess and a forwardly 10 facing opening at its top, light-creating means in said recess and behind said casing, said light-creating means including a bulb, a socket and an upwardly facing reflector, cooperating means on said light-creating means and on said casing to 15 position said light-creating means removably, and a reflector in said recess behind said opening and above said means, said reflector being so arranged that light rays are deflected forwardly and downwardly through said opening onto a surface cov- 20 ering undergoing cleaning.

5. A suction cleaner comprising a casing formed with an interior recess having a forwardly facing opening at the top thereof, a source of light mounted in said recess and positioned wholly 25 below the said opening, and means for reflecting the light rays emanating from said source of light outwardly through said opening.

6. A suction cleaner, comprising a casing having an interior recess provided with a forwardly 30 facing opening along the top thereof, a source of light mounted in said recess below said opening and completely concealed from view from the front of said casing, and a reflector mounted in said recess and so arranged that the rays from 35 said light source below the same are directed forwardly and downwardly through said opening.

DONALD G. SMELLIE.
